UNITED STATES PATENT OFFICE.

HARRY WILLIAMS, OF RETURN, VIRGINIA.

TIDE-MOTOR.

1,393,472.

Specification of Letters Patent. Patented Oct. 11, 1921.

Application filed February 28, 1920. Serial No. 362,045.

To all whom it may concern:

Be it known that I, HARRY WILLIAMS, a citizen of the United States, residing at Return, in the county of Caroline and State of Virginia, have invented certain new and useful Improvements in Tide-Motors, of which the following is a specification.

This invention relates to motors, and the primary object of the invention is to provide 10 an improved motor operated by the tide, whereby the power from the tide can be utilized for commercial purposes.

Another object of the invention is to provide an improved means for operating an 15 electric generator by the tide, so that coast and nearby cities may be provided with electric power without necessitating the erection and maintenance of costly plants now in vogue.

20 A further object of the invention is to provide an improved tide motor having means for continuously rotating a shaft in one direction, both on the incoming or flood tide and on the outgoing or ebb tide.

25 A further object of the invention is to provide an improved tide motor including a float or barge arranged to slidably receive oppositely facing rack bars anchored to the floor of the ocean, the barge carrying an operating shaft having operatively connected thereto by a train of speed advancing gears, a power transmitting cog arranged to engage the rack bars, certain of the cogs being adapted to operate the shaft on the rising of 30 the barge by the incoming tide and others being arranged to operate the shaft on the lowering of the barge at the ebb tide whereby the shaft will be rotated in a single direction.

35 A still further object of the invention is to provide means for storing the surplus electrical energy in a storage battery or the like during the rising and falling of the tide and for automatically placing the storage 45 battery in circuit with the motor, when the tide is at rest, when the same has reached the extreme height during the flood tide and at the ebb tide, so that the shaft will be continuously rotated during said rest periods.

40 A still further object of the invention is to provide an improved tide motor for operating an electric generator of the above character, which is durable and efficient in 50 use, one that is simple and easy to manufac-

ture, and one which can be placed upon the market at a reasonable cost.

Other objects of the invention will appear in the following detailed description taken in connection with the drawings, forming a 60 part of this specification, in which drawings:

Figure 1 is a plan view of the improved tide motor.

Fig. 2 is a central view taken on the line 65 2-2 of Fig. 1.

Fig. 3 is an enlarged vertical section taken on the line 3-3 of Fig. 1.

Fig. 4 is a diagrammatic view of the wiring for the generator and electric motor, and 70

Fig. 5 is an enlarged fragmentary detail section taken on the line 5-5 of Fig. 1 and illustrating a power transmitting cog engaging one of the rack bars disposed opposite to the rack bars which are engaged by the cogs 75 on the opposite side of the float shown in Fig. 2 of the drawings.

Referring to the drawings in detail, wherein similar reference characters designate corresponding parts throughout the several 80 views, the letter A indicates the improved tide motor which includes the barge or float B and the stationary piers C which are anchored to the bed of the ocean or the like. The barge B may be built of any desired 85 material, such as wood, metal, concrete or the like, and may be formed of any desired size so as to obtain the amount of power desired. The barge or float B is of substantially rectangular configuration and includes 90 the upper wall or deck 10, the bottom 11, and the side and end walls 12. The top wall or deck 10 may support a suitable housing for the mechanism of the motor if so desired, and a suitable home or office may be 95 erected on the float for the workman or attendant.

The float B at its four corners is provided with two pairs of spaced openings or slots 13 and 14, through which slidably protrudes the piers C which will be hereinafter more fully described. The walls of the pairs of slots 13 and 14 are provided with inwardly extending recesses 15 in which are rotatably mounted suitable rollers 16 which are adapt- 105 ed to engage the outer faces of the gears C so as to permit the free movement of the float or barge B in relation to the piers.

The piers C includes two pairs of spaced standards 17 and 18 located at the opposite 110

corners of the float and these standards slidably extend through the openings 13 and 14 formed in the barge. The pairs of spaced standards 17 and 18 are anchored in concrete or similar bases 19, which are embedded in the floor of the ocean. The pairs of standards 17 are located adjacent to the outer ends of the barge, while the standards 18 are arranged adjacent to the inner portion of the barge. Located on the opposite sides of the standards 17 and 18 are positioned upstanding bearing brackets 20 which rotatably support the guide shafts 21 and 22, which are arranged in spaced relation to one another. The outer ends of the guide shafts 21 and 22 carry master pinions 23 and 24, and the pinions 23 which are arranged between the standards 17 are adapted to engage rack bars 25, formed on the inner face of the innermost standard of the pair of standards 17. The master pinions 25 engage rack bars 26 formed on the inner face of the outermost standards of the pairs of standards 18 for a purpose which will hereinafter more fully appear. The rack bars 25 and 26 terminate short of the upper and lower ends of the standards so that the master pinions 23 and 24 will be carried out of engagement with the rack bars 25 and 26 when the barge has been lifted to the extreme height of the flood or ebb tide for a purpose which will be hereinafter more fully described. The shafts 21 and 22 are operatively connected to the main drive shaft 27, which is arranged adjacent to the longitudinal center of the barge by speed advancing gears 28, which are arranged on the opposite sides of the barge. The shaft 27 drives an electric generator 29 from which power is adapted to be taken for operating various devices. An electric motor 30 is also operatively connected to the shaft 27 for driving the shaft when the barge has risen to the highest point or lowest point at the flood and ebb tide, when the master pinions 23 and 24 have risen out of engagement with the rack bars 25 and 26. The shafts 21 and 22 have keyed or otherwise secured thereto, the relatively large gear wheels 31, which mesh with relatively small pinions 32, keyed to the shafts 33 which are arranged in parallel relation to the shafts 21 and 22. The shafts 33 have keyed or otherwise secured thereto the relatively large gear wheels 34 which in turn mesh with the relatively small gear wheels 35 keyed to the parallel arranged shafts 36. The shafts 36 in turn carry relatively large gear wheels 37 which mesh with the relatively small wheels 38 keyed to the shafts 39. The shafts 39 carries relatively large gear wheels 40 which mesh with the opposite sides of the relatively small pinions 41 keyed to the shaft 27. The gear wheels 31, 32, 34, 35, 37 and 38 and the shafts 21, 33, 36, and

39 form the speed advancing mechanism and it is to be understood that as many shafts with the relatively large and small gear wheels may be provided as is found necessary or applicable. The master pinions 23 and 24 have arranged adjacent thereto the ratchet wheels 42 which are keyed to the shafts 21 and 22. The master pinions 23 and 24 carry oppositely disposed dogs 43 which are pivotally connected to the master pinions 23 and 24 by suitable pins 44, and are normally urged into engagement with the ratchet wheel by a spring 45. By arranging the dogs 43 in opposite relation to each other, it can be seen that when the float is being raised by the flood tide, motion will be transmitted to the master pinion 23 in a clockwise direction, which will in turn rotate the drive shaft 27 in a clockwise direction. When the barge is being lowered, however, by the ebb tide, if the gears 23 were keyed to the shafts 21 and 22 the same could be driven in a counter clockwise direction and thus not rotate the drive shaft 27 in one direction at all times. When the barge is being lowered on the ebb tide, the master pinions 24 engaging the rack bars 26 and will be rotated in a counter clockwise direction which will in turn transmit their motion to the shafts 21 through the medium of the ratchet wheel 42 which in turn will rotate the drive shaft 27 in a clockwise direction. Thus it will be seen that the drive shaft 27 is turned in one continuous direction on the rise and fall of the tide. The relatively heavy balance or fly wheels 46 are keyed to the drive shaft 27 so that the inertia thereof will tend to rotate the drive shaft 27 at an even speed and continue the rotation thereof when the master pinions 23 and 24 ride out of engagement with the rack bars 25 and 26.

The upper terminals of the pairs of posts 17 and 18 are connected together by suitable braces 47, which prevents relative lateral movement of the posts or standards in relation to one another. The generator 29 has line wires 48 and 49 connected thereto which extend to the shore so that the current generated may be used for any purpose such as heating or lighting nearby cities. The wires 48 and 49 have also electrically connected thereto conductor wires 50 and 51 which lead to the opposite terminals of a storage battery 52 which is arranged in the bottom of the barge or float B. The wire 51 has a current reducer 53 arranged therein so as to reduce the voltage of the current from the generator to the storage battery, and this wire has also interposed therein an automatic cut out 54, so that when the battery pressure becomes greater than that induced by the generator, the battery will be automatically cut off from the generator. The motor 30 has line wires 55 and 56 connected

thereto and the line 55 extends to one terminal of the storage battery 52, while the opposite terminal of the storage battery has secured thereto a wire 57 which leads to a plug 58 of conducting material embedded in the standard in the piers C. The conductor plug 58 is embedded in a suitable insulation 59. The conductor plug 58 is arranged directly below the rack bars 25 and 26 so that when the float or barge B sinks below the rack bars, and thus not actuate the shaft 27, the circuit to the motor will be closed and thus permit the driving of the shaft. Arranged in spaced relation to the conductor plug 58 is a conductor plug 60 which is embedded in a suitable insulating sleeve 61, carried by the piers C. This plug 60 is arranged above the rack bars 25 and 26, so that when the barge have been raised to its highest point by the flood tide and the master pinion has been carried out of engagement with the rack bars the circuit to the motor 30 will be closed so as to continue the rotation of the shaft 27. The plugs 60 and 58 are connected by a suitable wire 62 which is embedded in the piers C. The circuit is closed to the motor by means of a contact 63 which is connected to the wire 66. The contact 63 is secured to the upstanding bracket 64 carried by the upper edge of the float. Thus it will be seen that when the barge reaches its uppermost and lowermost position, the contact 63 will come into engagement with either the conducting plug 60 or 58 and close the circuit to the storage battery 52. The storage battery 52 serves to drive the motor 30 and turn the shaft 27 for operating the generator until the tide starts to again rise or fall.

The shafts 33, 36 and 37 are mounted in suitable bearings 56 secured to the upper surface of the plate. The arrangement of the piers in relation to the barge or float steadies the same and transmits a steady uninterrupted flow of power to the drive shaft 27.

From the foregoing description it can be seen that an improved tide motor is provided, which is of exceptionally simple and durable construction and which will effectively accomplish the purpose intended.

Changes in details may be made without departing from the spirit or scope of the invention; but,

I claim:

- 55 1. A tide motor comprising a plurality of spaced pairs of standards, a barge slidably mounted on the standards, oppositely disposed rack bars formed on the inner faces of the standards, an operating shaft rotatably carried by the barge, rotatable shafts carried by the barge and arranged intermediate the rack bars, pinions meshing with the rack bars and carried by the second mentioned shaft, speed advancing mechanism operatively connecting the second
- 60 mentioned shafts with the operating shaft, a generator, means operatively connecting the shaft with the generator, and a storage battery connected with the generator, an electric motor operatively connected to the shaft, and means electrically connecting the battery with the motor.
- 65 2. A tide motor comprising a plurality of pairs of spaced standards, a barge slidably mounted on the standards, oppositely disposed rack bars formed on the standards, shafts rotatably carried by the barge and disposed between the rack bars, pinions carried by the shafts and arranged to engage the rack bars, an operating shaft, speed advancing mechanism operatively connecting the first mentioned shafts with the operating shaft, an electric generator operatively connected to the operating shaft, a storage battery connected to the generator, means for automatically cutting out the storage battery from the generator when the generator is below normal, an electric motor operatively connected to the shaft, an electric circuit connecting the storage battery with the motor, and means for closing the circuit through the electric motor when the float reaches its highest and lowest point.
- 70 3. A tide motor comprising a plurality of spaced pairs of supporting standards, a barge slidably mounted on the standards, oppositely disposed rack bars formed on the standards, shafts rotatably carried by the barge and arranged intermediate the rack bars, pinions carried by the shafts and arranged to engage the rack bars, ratchet wheels keyed to the shafts, dogs carried by the pinions and arranged to engage the ratchet wheels, an operating shaft, speed advancing mechanism operatively connecting the first mentioned shafts with the operating shaft, the rack bars ending short of the upper and lower terminals of the supporting standards, spaced contacts arranged above and below the rack bars, a generator, means operatively connecting the operating shaft with the generator, a storage battery electrically connected with the generator and an electric motor connected with the operating shaft, an electric circuit connecting the motor with the storage battery, spaced contact points arranged above and below the rack bar arranged in the circuit, and a second contact carried by the barge and arranged in the circuit for closing the circuit through the motor when the barge is in its upper and lowermost positions.
- 75 4. A tide motor comprising a plurality of pairs of spaced standards, oppositely disposed rack bars formed on the standards, the rack bars ending short of the upper and lower terminals of the standards, a barge slidably mounted on the standards, a ro-

latable shaft carried by the barge and disposed intermediate the rack bars, an operating shaft, speed advancing mechanism operatively connecting the first mentioned
5 shaft with the operating shaft, pinions carried by the first mentioned shaft arranged to engage the rack bars, ratchet wheels keyed to the first mentioned shaft, pivoted dogs carried by the pinions and arranged
10 to engage the ratchet wheels, a generator, means operatively connecting the generator with the operating shaft, a storage battery electrically connected with the generator, an electric motor operatively connected with

the operating shaft, a pair of spaced contacts embedded in one of the standards, an electric wire connecting the contact points, means connecting the contact points to one terminal of the battery, means operatively connecting the opposite terminal of the battery to one terminal of the motor, a contact carried by the barge, and arranged to engage the contacts carried by the standard, an electric wire connected to the opposite terminal of the motor and to the last mentioned contact. 15 20 25

HARRY WILLIAMS.
